ELECTRIC CIRCUIT CONTROLLING DEVICE

Joseph Sachs, West Hartford, Conn.

Application January 30, 1935, Serial No. 4,016

10 Claims. (Cl. 200—114)

The invention is particularly applicable to an electric circuit controlling device having a main base with circuit connections thereon and having main fuses which are mounted upon a removable carrier. In a device of this character the removal of the carrier and the fuses from the base serves to break the circuit and the device thus functions as a switch.

One of the objects of the present invention is to provide a device of the character described wherein there is a manually adjustable device which serves in one position to prevent the removable carrier from entering the base sufficiently to reestablish the electrical connection.

15 Other objects of the invention will be apparent from the following specification and claims.

In the accompanying drawing three alternative embodiments of the invention are disclosed, but it will be understood that the drawing is intended for illustrative purposes only and is not to be construed as defining or limiting the scope of the invention, the claims forming a part of this specification being relied upon for that purpose.

25 Of the drawing:

Fig. 1 is a front view of a device embodying the invention.

Fig. 2 is a front view similar to Fig. 1 but showing the adjustable element in a different position.

Fig. 3 is a vertical sectional view taken along the line 3—3 of Fig. 1.

Fig. 4 is a combined side and vertical sectional view similar to Fig. 3 but showing the adjustable element in position to prevent full entry of the carrier and of the parts thereon.

Figs. 5 and 6 are views similar respectively to Figs. 1 and 2 but showing an alternative embodiment of the invention.

40 Fig. 7 is a fragmentary view in some respects similar to Fig. 1 but showing another alternative embodiment of the invention. In this view the fuse carrier is omitted.

Fig. 8 is a transverse sectional view taken along the line 8—8 of Fig. 7 and also showing the fuse carrier and fuses in section.

Fig. 9 is a view similar to Fig. 8 but showing the adjustable element in position to prevent full entry of the fuse and carrier and the parts 50 thereon.

Referring to the drawing, particularly Figs. 1 to 4 thereof, 1 represents a main insulating base which is adapted to be secured to a suitable rear supporting wall, as for instance the rear wall of 55 an enclosing cabinet. The cabinet does not of

itself constitute any part of the present invention and it is not shown.

The base 1 is provided with at least one recess 2 adapted to receive a removable fuse carrier. There may be two or more such recesses but only 5 one is shown. The recess 2 is closed or substantially closed at the top, bottom and both sides and also the rear but is open at the front.

Carried by the main base near the rear there-of is at least one pair of electrical contacts 3 and 4, and preferably there are two pairs of contacts. Formed at the rear of the recess 2 are openings or slots 5, 5 and 6, 6 which are in register with the respective contacts 3, 3 and 4, 4, as clearly shown in Figs. 3 and 4.

10 The base 1 is provided with an upward projecting ledge 1^a and an integral portion of each contact 3 extends upward along the front of this ledge and is held in place by a forward extending screw 7. Also held by the screw 7 is a wire terminal 8. The base 1 is also provided with a downward projecting ledge 1^b and an integral portion of each contact 4 extends downward along the front face of this ledge. The said portion of the contact is held in place by a forward 15 extending screw 9. Also held by the screw is a wire terminal 10.

20 A fuse carrier 11 is provided which is preferably of insulating material and which is adapted to enter and approximately fit the recess 2 in the base 1. The fuse carrier 11 is provided on its rear face with at least one pair of contacts 12 and 13 adapted to receive a cartridge fuse, and preferably there are two pairs of such contacts. Also carried by the fuse carrier is at 25 least one pair of conducting blades or prongs 14 and 15 which are electrically connected with the corresponding fuse contacts. When there are two pairs of fuse contacts there are two pairs of conducting prongs. The fuse carrier is 30 preferably provided at the front with a suitable pivoted handle 16 by means of which the carrier 35 may be conveniently withdrawn from the recess.

When the carrier is in its normal fully entered position, as shown in Figs. 1 and 3, the conducting prongs 14 and 15 of each pair engage respectively with the corresponding stationary contacts 3 and 4, and in this manner a circuit through the device is established, provided of course that there are fuses in place in the several contacts 12 and 13. The fuses are concealed and access can be had to them for purposes of inspection or replacement only by entirely removing the fuse carrier from the base and thus 40 45 50 55

withdrawing the prongs 14 and 15 from the contacts 3 and 4 so as to break the circuit and completely disconnect the fuses.

The base 1 may be provided with integral ribs 5 or barriers 2^a, 2^b located within the recess 2 and positioned between the respective fuse contacts when the carrier 11 is in its normal position. The carrier may have grooves for receiving the forward edge portions of the barriers.

10 The removable fuse carrier may be withdrawn from the recess in the base not only for the purpose of inspecting or renewing the fuses but also for the purpose of breaking the circuit. When the purpose is to maintain the interruption of the circuit it is desirable to replace the fuse carrier in the device in such a manner that it may be conveniently retained, but without there being any possibility of accidental reestablishment of the circuit. In accordance with the present invention a manually adjustable element 17 is provided which serves in one position to permit the carrier 11 and the parts thereon to fully enter the recess 2 and which serves in another position to prevent such entry and to thereby prevent engagement of the blades 14 and 15 with the contacts 3 and 4. The adjustable element 17 may be constructed and mounted in a variety of ways, but in Figs. 1 to 4 it is shown as being mounted on the removable carrier and pivoted so as to be capable of movement about an axis perpendicular to the fuse axes and positioned between the said axes. As shown in these figures, the said element 17 is a flat plate, preferably formed of insulating material and pivoted on the same screw 18 which serves to connect the handle 16 with the carrier. Preferably pins 19, 19 are provided for limiting the pivotal movement of the element 17.

40 The base and the carrier are provided with ribs and grooves which are adapted to fit each other, and while the form and arrangement of these ribs and grooves may be varied I have shown opposite ribs 1^c, 1^c formed on the base at the sides of the recess 2, and I have shown 45 grooves 11^a, 11^a formed in the carrier and adapted to receive the ribs 1^c, 1^c. With the element 17 in the position shown in dotted lines in Fig. 1 and shown in full lines in Fig. 3, the carrier can be fully entered in the recess in the base so 50 as to bring the prongs 14 and 15 into full engagement with the contacts 3 and 4. However, when the element 17 is turned to the position shown by dotted lines in Fig. 2 and shown by full lines in Fig. 4, the corners thereof are in 55 register with the grooves 11^a, 11^a, the result being that the said corners of the element 17 engage the ends of the ribs 1^c, 1^c to prevent complete entry of the carrier and the parts thereon into the recess 2. The carrier and the associated parts are held in the position shown in 60 Fig. 4 with the prongs 14 and 15 out of engagement with the contacts 3 and 4. In this position the prongs 14 and 15 engage the walls of the recess 2 sufficiently to hold the carrier and associated parts in place and to prevent it from falling out.

The construction shown in Figs. 5 and 6 differs from that shown in Figs. 1 to 4 in that the slots and grooves at the sides are omitted. In lieu of the adjustable element 17 there is provided an adjustable element 28 which is similarly pivoted but different in shape. With the element 28 in the position shown in Fig. 5 the carrier 11^b with the parts thereon can be fully entered

in the recess in the base. With the element 28 in the position shown in Fig. 6 the ends thereof engage the front edge of the ribs or barriers 2^a, 2^b and prevent the carrier from entering, holding it in a position approximately the same as that shown in Fig. 4.

The construction shown in Figs. 7, 8 and 9 is somewhat different from the constructions already described in that the adjustable element 17 is carried by the base instead of by the removable carrier. The base and carrier may be similar to those shown in Figs. 5 and 6.

While the position and manner of mounting of the adjustable element may be varied, it is preferably a pivoted element 21 connected so as to be capable of movement about an axis perpendicular to the fuse axes and positioned between the said axes. As shown, the base is provided with a centrally disposed hole, and a cotter pin 22 is provided which projects through a central hole in the element 21 and through the hole in the base and serves as a pivot for the said element 21. The element 21 is cut away at the sides so that, when it is in the position shown in Fig. 8 and shown by full lines in Fig. 7, clearance is provided for the fuses F, F, and the carrier with the parts thereon can be fully entered. However, when the element 21 is turned to the position shown in Fig. 9 and shown by dotted lines in Fig. 7, the corners of the said element interfere directly with the fuses F, F to prevent entry of the carrier and their parts.

What I claim is:

1. In a device of the class described, the combination of an insulating base having a recess open at the front, two electrical contacts near the rear of the base and adjacent opposite ends of the recess, a removable carrier adapted to be positioned within the recess and having electrically connected contacts thereon adapted to be engaged with or disengaged from the contacts on the base, and a manually adjustable element normally within the recess and serving in one position to permit the carrier to be moved into normal relationship to the base with the contacts thereon engaged with the contacts on the base and serving in another position to prevent the carrier from moving sufficiently to enable the contacts thereon to engage the contacts on the base. 35

2. In a device of the class described, the combination of an insulating base having a recess open at the front, two electrical contacts near the rear of the base and adjacent opposite ends of the recess, a removable fuse carrier adapted to be positioned within the recess, fuse contacts on the carrier at the rear thereof and electrically connected with the respective fuse contacts, conducting prongs on the carrier at the rear thereof and electrically connected with the respective fuse contacts, the said prongs extending rearward and engaging the contacts on the base when the carrier is in normal relationship to the base, and a manually adjustable element normally within the recess and serving in one position to permit the carrier to be moved into its normal relationship to the base and serving in another position to prevent the carrier from moving rearward sufficiently to enable the prongs to engage the contacts on the base. 50

3. In a device of the class described, the combination of an insulating base having a recess open at the front, two electrical contacts near the rear of the base and adjacent opposite ends of the recess, a removable fuse carrier adapted 75

to be positioned within the recess, fuse contacts on the carrier at the rear thereof, conducting prongs on the carrier at the rear thereof and electrically connected with the respective fuse contacts, the said prongs extending rearward and engaging the contacts on the base when the carrier is fully entered in the recess, and a manually adjustable pivoted element normally within the recess and serving in one position 10 of pivotal adjustment to permit the carrier to fully enter the recess and serving in another position of pivotal adjustment to prevent such entry and to thereby prevent engagement of the prongs with the contacts on the base.

15 4. In a device of the class described, the combination of an insulating base having a recess open at the front, two electrical contacts near the rear of the base and adjacent opposite ends of the recess, a removable fuse carrier adapted 20 to be positioned within the recess, fuse contacts on the carrier at the rear thereof, conducting blades on the carrier at the rear thereof and electrically connected with the respective fuse contacts, the said blades extending rearward and 25 engaging the contacts on the base when the carrier is fully entered in the recess, and a manually adjustable element normally within the recess and pivotally movable about an axis perpendicular to and between the fuse axes, the 30 said element serving in one position of pivotal adjustment to permit the carrier to fully enter the recess and serving in another position of pivotal adjustment to prevent such entry and to thereby prevent engagement of the blades with 35 the contacts on the base.

5. The combination of an insulating base having a recess open at the front, two electrical contacts near the rear of the base and adjacent opposite ends of the recess, a removable fuse carrier adapted to be positioned within the recess, fuse contacts on the carrier at the rear thereof, conducting blades on the carrier at the rear thereof and electrically connected with the respective fuse contacts, the said blades extending rearward and engaging the contacts on the base when the carrier is fully entered in the recess, and a manually adjustable element mounted on the carrier and normally positioned within the recess, the said element serving in one position to permit the carrier to fully enter the recess and serving in another position to prevent such entry and to thereby prevent engagement of the blades with the contacts on the base.

6. The combination of an insulating base having a recess open at the front, two electrical contacts near the rear of the base and adjacent opposite ends of the recess, a removable fuse carrier adapted to be positioned within the recess, fuse contacts on the carrier at the rear thereof, conducting blades on the carrier at the rear thereof and electrically connected with the respective fuse contacts, the said blades extending rearward and engaging the contacts on the base when the carrier is fully entered in the recess, and a manually adjustable pivoted element mounted on the carrier and normally positioned within the recess, the said element serving in one position of pivotal adjustment to permit the carrier to fully enter the recess and serving in another position of pivotal adjustment to prevent such entry and to thereby prevent engagement of the blades with the contacts on the base.

7. The combination of an insulating base having a recess open at the front and having a rib

within the recess, two electrical contacts near the rear of the base and adjacent opposite ends of the recess, a removable fuse carrier adapted to be positioned within the recess and having a groove positioned to receive the rib on the base, 5 fuse contacts on the carrier at the rear thereof, conducting blades on the carrier at the rear thereof and electrically connected with the respective fuse contacts, the said blades extending rearward and engaging the contacts on the base when the carrier is fully entered in the recess, and a manually adjustable element mounted on the carrier and serving in one position to permit the carrier to fully enter the recess and serving in another position to engage the end of the rib 10 to prevent such entry and to thereby prevent engagement of the blades with the contacts on the base. 15

8. The combination in a device of the class described, of an insulating base having a recess open at the front, two electrical contacts near the rear of the base and adjacent opposite ends of the recess, a removable fuse carrier adapted 20 to be positioned within the recess, fuse contacts on the carrier at the rear thereof, conducting blades on the carrier at the rear thereof and electrically connected with the respective fuse contacts, the said blades extending rearward and 25 engaging the contacts on the base when the carrier is fully entered in the recess, and a manually adjustable element mounted on the base within the recess and serving in one position to 30 permit the carrier to fully enter the recess and serving in another position to prevent such entry and to thereby prevent engagement of the blades 35 with the contacts on the base.

9. The combination in a device of the class described, of an insulating base having a recess open at the front, two electrical contacts near the rear of the base and adjacent opposite ends 40 of the recess, a removable fuse carrier adapted to be positioned within the recess, fuse contacts on the carrier at the rear thereof, conducting blades on the carrier at the rear thereof and electrically connected with the respective fuse contacts, the said blades extending rearward and 45 engaging the contacts on the base when the carrier is fully entered in the recess, and a manually adjustable pivoted element mounted on the base within the recess and serving in one position 50 of pivotal adjustment to permit the carrier to fully enter the recess and serving in another position of pivotal adjustment to prevent such entry and to thereby prevent engagement of the blades with the contacts on the base. 55

10. The combination in a device of the class described, of an insulating base having a recess open at the front, two electrical contacts near the rear of the base and adjacent opposite ends of the recess, a removable fuse carrier adapted to 60 be positioned within the recess, fuse contacts on the carrier at the rear thereof, conducting blades on the carrier at the rear thereof and electrically connected with the respective fuse contacts, the said blades extending rearward and engaging the 65 contacts on the base when the carrier is fully entered in the recess, and a manually adjustable element mounted on the base and serving in one position to permit the carrier to fully enter the recess and serving in another position to engage fuses in the fuse contacts and prevent such 70 entry and to thereby prevent engagement of the blades with the contacts on the base.

JOSEPH SACHS.
